(57) **CLAIM**

The ornamental design for a motor vehicle hood part, as shown and described.

DESCRIPTION

A portion of the disclosure of this patent document contains material to which a claim for copyright is made. The copyright owner has no objection to the facsimile reproduction by anyone of the patent document or the patent disclosure as it appears in the Patent and Trademark Office patent file or records, but reserves all other copyright rights whatsoever.

FIG. 1 is a top plan view of a motor vehicle hood part showing my new design;

FIG. 2 is a bottom plan view thereof;

FIG. 3 is a right elevation view thereof;

FIG. 4 is a left elevation view thereof;

FIG. 5 is a front elevation view thereof; and,

FIG. 6 is a back elevation view thereof.
